UNITED STATES PATENT OFFICE

HARLAN S. GANO, OF MANSFIELD, OHIO, ASSIGNOR TO WESTINGHOUSE ELECTRIC & MANUFACTURING COMPANY, A CORPORATION OF PENNSYLVANIA

FURNACE CYCLE CONTROL

Application filed November 30, 1926. Serial No. 151,694.

My invention relates to furnace cycle control systems and particularly to electrical control systems for rotary furnaces.

An object of my invention is to provide an efficient cycle control system for a furnace.

Another object of my invention is to provide an automatic control system for an intermittently operating rotary furnace.

Another object of my invention is to provide electric means for chronometrically controlling the operation of a conveyer and of a hearth-tray dumping mechanism in a furnace.

Another object of my invention is to provide means for preventing simultaneous operation of a conveyer and of a tilting mechanism.

Another object of my invention is to provide an automatically-actuated mechanism for operating the charging door of a furnace.

Another object of my invention is to provide a control system for a plural-hearth-tray rotary furnace, in which means operatively associated with the rotary hearth de-energizes a hearth turning motor, which, in turn, energizes a tray-tilting motor, re-energizes the hearth-turning motor and then de-energizes its own circuit, this cycle being continued indefinitely.

Another object of my invention is to provide manual control means for a furnace that shall operate independently of the automatic control.

Other objects of my invention will be apparent from the disclosure.

In practising my invention in accordance with the present embodiment, I provide separate electric motors for driving the conveyer and the hearth-tray dumping mechanism, respectively. Since these motors are intended to operate alternately, interlocking means are provided to prevent both motors operating at the same time.

Chronometric means is provided for controlling the operation of these motors. Such means is started by means controlled by the conveyer. The chronometric means periodically and alternately causes the energization of the conveyer-driving motor and of the tilting motor. The deenergization of the con-

veyer motor and of the tilting motor is caused by means controlled by the conveyer and the tilting mechanism, respectively. The chronometric means is self-stopping.

Pneumatic means is provided for opening the charging door. Such means is automatically governed by means controlled by the conveyer.

Manually operable means are provided for controlling the operation of the conveyer, the tilting mechanism and the charging door, independently of the automatic control means.

In the drawings,

Figure 1 is a view, in vertical section, of a furnace to which my control system is applied.

Fig. 2 is a view, in vertical section, of one-half of the furnace, showing the charging-door mechanism,

Fig. 3 is a diagram of the wiring of the control system,

Fig. 4 is a detail diagrammatic view of a modification of the timing drum, and

Fig. 5 is a view, in vertical section and on an enlarged scale, of a door-actuating means.

Referring to the drawing for a more detailed description of my invention, a furnace 10, shown in Figs. 1 and 2, comprises an outer cylindrical casing 12, an inner cylindrical casing 13 and an annular refractory heat and electric-insulating lining 14 within the casings, the lining 14 having an annular chamber 15 therein. Suitable supports 16 are provided for supporting the furnace.

Suitable heating means is provided and, in the present embodiment of my invention, such heating means comprises electric heating elements 18 positioned in the chamber 15 and secured to the chamber walls. These heating elements are connected to a source of energy (not shown).

An annular passage or run-way 20 is provided in the bottom of the furnace, the top thereof communicating with the annular chamber 15. An annular conveyor 22 comprises a refractory insulating portion 23 and a metallic bottom portion 24 and is of such dimensions as to permit of rotation in the annular passage 20. The bottom portion 24

is provided with a plurality of pairs of spaced integral depending lugs or flange members 25, wheels 27 being suitably mounted between the lugs of each pair. These 5 wheels run on a circular track 28, thus providing a means for rotatably supporting the conveyer 22. Suitable concentric sand seals 29 are provided to prevent heat loss by reason of convection currents of air through the 10 spaces between the walls of runway 20 and the conveyor 22.

Means are provided for driving the conveyer to cause it to rotate and, in the present embodiment, such means comprises a circular rack 30 that may be integral with the bottom portion 24 and is adapted to mesh with a bevel gear 31 that is keyed on one end of a shaft 32, which is rotatably mounted on a support 33. A bevel gear 34 is keyed to the 15 other end of the shaft 32 and engages a bevel gear 35 keyed on the lower end of a shaft 36 that extends vertically through the central portion of the furnace and is rotatably mounted in bearings 37 and 38.

20 The shaft 36 is held in place, at its upper end, by any suitable means, such as a collar 39. A bevel gear wheel 40 is rigidly secured to the upper end of the shaft 36 and engages a bevel gear pinion 41 that is rigidly secured 25 to a shaft 42 of a speed-reducing device comprising a worm gear in a casing 43 and a worm actuated by an electric motor 44. The motor may be designated the conveyor-driving 30 motor or the hearth-motor.

35 A plurality of hearth supports 45 are rigidly mounted at equal intervals on the top of the refractory insulating portion 23 of the conveyor 22. A material-receiving hearth tray 47 is pivotally secured, at its 40 outer end, to each hearth support normally in the position shown by the full lines (Figs. 1 and 2). The hearth trays 47 are open at their outer ends for a purpose hereinafter to be made clear. The inner ends of trays 45 47 extend beyond the hearth support 45 to permit engagement with means for periodically effecting the discharge of material from the hearth tray.

Such means, in the present embodiment of 50 my invention, consists of a tilting mechanism comprising a vertical shaft 50 slidably positioned in a passageway 51 and having a projection 52 that extends under the inner end of a hearth tray when the tray is opposite a discharge outlet 54 and above a quench tank 55. A connecting rod 56 operatively connects the shaft 50 with a gear wheel 58.

The gear wheel 58 is operatively connected, 55 through a speed reducing device 59, to a prime mover 60, that may be an electric motor. The gear wheel 58 engages a gear wheel 62 that has a substantially circular cam 63 associated therewith and driven thereby for a purpose hereinafter to be made clear. The 60 diameter of gear wheel 62 is the same as that

of gear wheel 58 so that they will operate at the same number of revolutions per minute. A sand seal 65 is provided to prevent heat loss upwardly through the passageway 51.

65 A charging door 67 is provided to normally close a charging opening 68, (see Fig. 2). The charging opening is preferably positioned close to the discharge outlet to permit the charging of a hearth tray that has been dumped there being one tray between them. This is to provide a space between the outlet and the charging opening. A charging platform 69 may be provided, if desired, in order to facilitate the charging of the successive trays.

70 Means are provided to automatically operate the door 67. Such means comprises, in the present embodiment of my invention, a pneumatically operated piston 70 (see Fig. 2) slidably fitting in a cylinder 72 and connected to one end of a piston rod 73 the other end of which is operatively connected to the charging door 67 by means of a cable 74 passing over a pulley 75. The weight of the door 75 is such that it will normally remain in its closed position and will hold the piston 70 near the outer end of the cylinder 72.

75 One end of a pipe 77 is connected to the outer end of the cylinder 70 and the other end thereof is connected to a chamber 78 of an air-valve housing 79 (see Figs. 2 and 5). The housing 79 comprises the central chamber 78, and upper chamber 80, a lower chamber 81 and partitions 82 and 83 that have valve seats 84 and 85, respectively, 80 therein.

85 A valve 86 is maintained normally seated on the valve seat 85 by means of a compression spring 87 located in the lower chamber 81. The valve 86 is secured to a valve rod 89. Spaced from the valve 86 and also secured to the valve rod 89 is a valve 90 that is adapted to seat on the valve seat 84 but is normally maintained in an open position by the spring 87.

90 Normally, the lower chamber 81 is not in communication with the chamber 78 while the chamber 80 is in communication therewith. The chamber 80 is provided with an outlet 91 that leads to the outside atmosphere. The chamber 81 is provided with an inlet pipe 92 that is connected to a source of compressed air (not shown).

95 Means for automatically operating the valve rod 89 comprises a core member 93 (see Figs. 1 and 3) of an electromagnet that is rigidly secured to the valve rod 89, a coil 94 for energizing said core member and means for energizing the solenoid to be hereinafter described.

100 It will be obvious from the foregoing, that, when the coil 94 is energized, the valve rod 89 will be moved downwardly to seat the valve 90 and to unseat the valve 86, and compressed air will flow from pipe 92 into cham-

ber 81 through the open seat 85 into the chamber 78 and the conduit 77 and into the outer end portion of the cylinder 72, and will operate the piston 70 against the weight of the door 67 and cause an upward movement of the door.

It will also be apparent from the drawing and the foregoing description that, when the motor 44 is operating, the conveyer 22 will be driven to cause the hearth trays 47 to progress through the chamber 15. It will also be apparent that, when the motor 60 is operated, the gear 58 will turn and the connecting rod 56, which is operatively secured thereto, will move the shaft 50 first upwardly and then downwardly. In moving upwardly, the shaft 50 will cause the projection 52 to engage the hearth tray 47 that is opposite to the discharge outlet 54, and the tray 20 will thereby be tilted to cause the heat-treated articles located thereon to fall through the discharge outlet 54 into the quench tank 55 that is preferably filled with oil to a level above the lower end of the discharge spout 54 and thus provide an oil seal for the discharge opening.

I provide control means for causing the periodical operation of the hearth conveyer, of the tilting mechanism and of the charging door mechanism. Preferably, in this type of furnace, the conveyer is stationary while the tilting mechanism is operating, and vice versa.

Fig. 3 shows one embodiment of my control system for periodically effecting the above-noted operations, in proper sequence. In addition to the motors 44 and 60 and the door operating air cylinder 79, a timing-device driving motor 101 is connected to a contact drum 102 through a variable-speed reduction device 103, the latter being shown schematically in the drawing, as it forms no essential part of my present invention. The device 103 may be of any suitable type purchasable in the market and effective to vary the rotating speed of the drum 102 within relatively wide and adjustable limits. The drum 102 is shown in Fig. 3 in a developed condition; that is, all of the peripheral surface of the drum is shown as located in one plane, in order to illustrate more clearly the shape of a conducting plate 104 secured to the surface thereof. The plate 104 comprises four integral portions 105, 106, 107, and 108, located in longitudinally spaced relation on the drum and all of substantially the same width. Portion 105 extends entirely around the periphery of the drum, and is engaged by a fixed contact brush 109. Portion 106 is shorter in the peripheral direction so that its peripheral extent is less than 360° and is engaged by a brush 111. Portion 107 is relatively short peripherally and is engaged by a brush 112, the portion being so located peripherally, that it is engaged by the brush very shortly after turning

movement of the drum 102 has been started. Portion 108 is also relatively short peripherally and is so located as to be engaged by a brush 113 when the drum has been turned through almost 360°. The axial width of the respective portions 105, 106, 107 and 108 is just sufficient to provide proper engaging surfaces for the respective contact brushes. The drum is to be rotated in the direction of the arrow shown beside the drum.

A triple-pole double-throw switch 114, having contact blades 115, 116 and 117 and cooperating fixed jaws, ensures circuit connections which will be hereinafter described in detail. When the switch 114 is in the position shown in Fig. 3, the control system is connected for automatic operation, but it may be controlled manually when the switch blades are thrown to the opposite position, as will be hereinafter described more in detail.

The motor 44 actuates intermittently a switch lever 118 that is pivotally mounted on a suitable fixed member, (not shown), by means of spaced lugs 119 secured to a portion of the rotating hearth, as is shown more particularly in the lower left-hand portion of Fig. 1 of the drawing. The lever switch 118 has its inner or roller end maintained in yielding engagement with a portion of the sand seal, hereinbefore described, by a suitable spring. The illustration of this device in Fig. 3 of the drawings is schematic only. The number of lugs 119 is equal to the number of hearth trays 47. The outer or contact end of the lever 118 normally engages a fixed contact member 121 but is disengaged therefrom and caused to engage a second contact member 122 when the inner end of the lever is engaged by one of the lugs 119. The peripheral width of the respective lugs 119 is such that the lever 118 engages contact member 122 for a very short time only, this time being that when one tray has arrived in a position for unloading material located thereon and when, simultaneously, the second preceding tray is in position for reloading. No mounting means for contact members 121 and 122 is shown in either Fig. 1 or Fig. 3 of the drawings, as any support suitable for the purpose may be employed.

The motor 60 actuates a cam 63 having a single relatively narrow depression in its peripheral surface, which surface is engaged by the inner or roller ends of two switch levers 123 and 124, which are pivotally mounted on suitable means, not shown, intermediate their ends. The outer ends of the respective contact levers cooperate with substantially fixed contact members 125 and 126. The lever 123 is normally in engagement with its cooperating contact member 125 and disengagement therebetween is effected only when the roller end thereof drops into the single recess in the cam surface. The lever 124 is normally out of engagement with the contact member 126

and is in engagement therewith only when the roller end thereof engages the recess in the cam 63.

A main source of energy for the hearth-moving motor and the tray-tilting motor comprises conductors 131, 132 and 133 of a three-phase circuit, a circuit breaker 134 being provided for motor 44 and a circuit breaker 135 being provided for motor 60, these circuit breakers having holding coils 136 and 137, respectively, cooperating with core members in a manner well known in the art and back contact and cooperating bridging members 138 and 139, respectively. Circuit breakers 134 and 135 are of the three-phase type provided with fixed contact members and movable bridging members, which are maintained out of engagement with each other by spring means and which are maintained in engagement with each other to close the circuit through the motor by the holding coils 136 and 137, respectively. The showing of the back bridging members 138 and 139 is intended to be schematic only, the main essential being that the circuits through the bridging members 138 and 139 shall be closed thereby when the circuits through the main or front bridging members of the respective circuit breakers are open. That is, the single-conductor circuit is closed when the three-phase circuit is open, and vice versa.

For the purpose of energizing the control system and for providing energy for other purposes to be hereinafter set forth in detail, auxiliary conductors 141 and 142 and a plurality of circuits adapted to receive energy therefrom are provided.

For the sake of clearness, such circuits may be designated as an overload-relay circuit, the periodic hearth-motor starting circuit, the tilting-motor starting circuit, the tilting-motor holding circuit, the timing-motor starting circuit, the timing-motor holding circuit, the timing-motor energizing circuit, the hearth-motor inching circuit, the tilting-motor inching circuit, the air-valve-solenoid energizing circuit, the air-valve-solenoid holding circuit, the automatically-controlled charging-door operating circuit, and the manually-controlled charging-door operating circuit, and these will hereinafter be described in detail.

The overload relay circuit for motors 44 and 60 comprises conductor 141, a push-button off-and-on switch 143, a conductor 144, contact and bridging members of an overload relay 145 associated with the motor 60, conductor 146, contact and bridging members of an overload relay 147 associated with motor 44, conductor 148, switch blade 117, conductor 149, conductor 151, lever arm 118, contact member 121, conductors 152 and 153, switch blade 115, conductor 154, coil 136 of circuit breaker 134, conductor 155, back bridging member 139, conductors 156 and 157, to con-

ductor 142. Relays designated by numerals 145 and 147 are overload relays, the coils of which are connected in the respective motor circuits between the circuit breakers and the stator coils on the respective motors, the coils thereby being traversed by the same current as traverses the respective phases of the circuit breakers, and the respective phase windings of the motors. While a single overload coil only is shown, I may provide two such coils, connected in different phase circuits and energizing a single core member.

In case an excessive current traverses a circuit breaker, motor and overload relay, the core member of the relay will be moved upwardly to disengage the bridging member from the stationary contact members. As these relays are substantially standard devices, the detail elements thereof are not provided with reference numerals.

In case either the motor 44 or the motor 60 is overloaded, for any reason whatsoever, so that an excessive current traverses them and their cooperating relay coils, the relays 147 or 145 will be energized and will open the circuit from the main conductor through the cooperating respective holding coils 136 and 137, to cause opening of the cooperating circuit breaker and thereby deenergize the motor.

The timing-motor starting circuit comprises conductor 142, a part of conductor 157, the coil of a relay 158, which controls the timing-motor circuit, conductor 159, contact member 122, lever switch 118, conductors 151 and 149, blade 117, conductor 148, bridging member of relay 147, conductor 146, bridging member of relay 145, conductor 144, switch 143 and back to the other auxiliary supply-circuit conductor 141. When the timing-motor starting circuit is closed, the relay 158 is energized and will close the timing-motor energizing circuit. This circuit comprises conductor 142, part of conductor 157, upper bridging member 161 of relay 158, the preferably synchronous motor 101, the lower bridging member 162 of relay 158 and, through conductor 163, to the auxiliary supply-circuit conductor 141.

The electric-conducting plate 104, hereinbefore described as being located on drum 102, is connected to supply-circuit conductor 141 by brush 109, through a conductor 164, part of conductor 151, conductor 149, blade 117, conductor 148, bridging member of relay 147, conductor 146, bridging member of relay 145, conductor 144, and switch 143, to supply circuit conductor 141. This circuit may be briefly designated, for future reference, as a "return circuit."

The timing-motor holding circuit comprises conductor 142, part of conductor 157, coil of relay 158, conductor 165, brush 111, portions 106 and 105 of plate 104 and brush 109 to line 141 by the above-described "return

circuit" which serves to maintain the coil of relay 158 energized after the timing-motor starting circuit has been opened by disengagement of switch 118 from contact member 122.

- 5 The tilting-motor starting circuit comprises conductor 157 connected to supply-circuit conductor 142, conductor 156, back bridging member 138, conductor 166, holding coil 137, conductor 167, blade 116, conductor 168, conductor 169, brush 112, portions 107 and 105 of plate 104 to brush 109 and back through the above-described "return circuit." The closing of this circuit upon turning 15 movement of the drum 102 starts the tilting motor.

The tilting-motor holding circuit comprises conductor 157 connected to supply-circuit conductor 142, part of conductor 156, 20 back bridging member 138, conductor 166, coil 137, conductor 167, blade 116, conductor 168, contact member 125, lever arm 123 associated with motor 60, conductors 171, 172, 151, and 149, blade 117, conductor 148, bridging member of relay 147, conductor 146, bridging member of coil 145, conductor 144 and through switch 143, to supply-circuit conductor 141. The closing of this circuit ensures energization of the tilting-motor independently of the drum.

30 The periodic hearth-motor starting circuit comprises conductor 157 connected to supply-circuit conductor 142, conductor 156, bridging member 139, conductor 155, coil 136, conductor 154, blade 115 and conductors 153 and 173 to brush 113, through portions 108 and 105 to brush 109 and from there back to the other supply-circuit conductor 141 by the above-described "return circuit."

40 The automatically-controlled charging-door operating circuit comprises a part of conductor 157 connected to supply-circuit conductor 142, conductors 186 and 185, a normally closed push-button switch 184, conductor 183, the coil of a relay 177, conductor 182, contact member 126, arm 124, conductors 171, 172, 151 and 149, blade 117, conductor 148, bridging member of relay 147, conductor 146, bridging member of relay 145, conductor 144 and switch 143 to supply-circuit conductor 141.

45 The air-valve-solenoid energizing circuit comprises conductor 141, switch 143, conductor 144, bridging member of relay 145, conductor 146, bridging member of relay 147, conductor 148, blade 117, conductor 149, 174 and 175, contact members and the lower bridging member 176 of relay 177, conductor 178, coil 94 of the air-valve device, conductors 179 and 186 and, through a part of conductor 157, to supply-circuit conductor 142.

50 The air-valve-solenoid holding circuit comprises conductor 141, switch 143, conductor 144, bridging member of relay 145, conductor 146, bridging member of relay 147, conductor

148, blade 117, conductors 149, 174 and 175, bridging member 181 of relay 177, conductor 182, coil of relay 177, conductor 183, push-button switch 184, conductors 185 and 186 and a part of conductor 157 to supply-circuit 70 conductor 142.

As has been noted hereinbefore, the system will operate automatically only so long as switch 114 is in the position shown in Fig. 3 of the drawings. When it is desired, for 75 any reason, to control the respective devices manually, the switch blades are thrown to the left and certain circuits may be energized as will be hereinafter set forth.

The hearth-motor inching circuit comprises conductor 142, conductors 157 and 156, bridging member 139, conductor 155, coil of relay 136, conductor 154, blade 115, conductor 187 to a normally open push-button switch 188, conductor 189, connected to one of the terminals of switch 188, conductor 148, bridging member of relay 147, conductor 146, bridging member of relay 145, conductor 144 and, through switch 143 to supply-circuit conductor 141. This circuit is, of course, energized only when switch 188 is held in its closed position, and if switch 114 is thrown to its left-hand position.

80 The tilting-motor inching circuit comprises conductor 142, conductor 157, a part of conductor 156, to the back bridging member 138, conductor 166, coil 137, conductor 167, to blade 116, conductor 191 to one terminal of a normally open push-button switch 192, conductor 189 which is connected also to one terminal of switch 192, conductor 148, bridging member of relay 147, conductor 146, bridging member of relay 145, conductor 144 and through switch 143, to conductor 141. This circuit is energized only so long as switch 100 192 is held closed by an operator, and when the switch 114 has been thrown to its left-hand position.

85 A manually-controllable charging-door energizing circuit comprises conductor 141, 110 switch 143, conductor 144, bridging member of relay 145, conductor 146, bridging member of relay 147, conductor 148, blade 117, conductors 149 and 174 through the contact members and the bridging member of a normally open push-button switch 193, conductor 194, conductor 182, coil of relay 177, conductor 183, through the normally closed push-button switch 184, conductors 185 and 186 and part of conductor 157 to the auxiliary 115 supply-circuit conductor 142. This circuit may be energized only when the switch 114 is in its right-hand position.

90 It will be evident from the foregoing description and drawings that, when the triple-pole switch 114 and the lever switch 118 are in the positions shown in Fig. 3 of the drawings, and when the switch 143 (which is shown in its open position but which will remain in either its open or its closed position after 120 125 130

having once been moved thereto and until again manually actuated to its other position) is closed, the main hearth-motor starting circuit will be closed, thus energizing coil 136, whereby the breaker 134 is closed, the motor 44 is energized and will actuate the hearth as hereinbefore described.

The motor 44 will drive conveyer 22 until a tray filled with the heat-treated material arrives opposite to the discharge outlet, at which time the roller end of switch lever 118 will be engaged by a lug 119, as shown in Fig. 1 of the drawings, and will be thrown to a position opposite to that shown in Fig. 3. In this position of the switch lever, the timing-motor starting circuit will be closed, thus energizing coil 158, closing the circuit through the timing motor by the bridging members 161 and 162.

The timing motor 60 being thus started will, in turn, cause the drum 102 to rotate, and the rotation thereof will cause the engagement of brushes 111 and 112 with the conducting surfaces 106 and 107, respectively, shortly after the drum has begun to turn. When the stationary contact member 111 engages the portion 106, the timing-motor-holding-circuit will be closed, through the coil of relay 158, to maintain the relay in its closed position independently of the initial energizing circuit closed by the switch 118, as previously described.

Since the switch 118 is in a position opposite to that shown in Fig. 3, the main hearth-motor starting circuit will be opened, relay 136 will be deenergized and breaker 134 will be in its open position so that motor 44 will be deenergized and the conveyer 22 will be stationary.

When stationary contact member 112 engages the portion 107 of the conducting surface 104, it is evident that the tilting-motor starting circuit will be closed, and coil 137 will be energized, thus effecting closing of circuit breaker 135, whereby tilting-motor 60 is energized and causes an upward and then a downward movement of the tilting means actuated by the motor 50, as has been hereinbefore described.

As the gear wheel 62 is in engagement with the gear wheel 58, it will be rotated when the tilting motor 60 is started. The cam 63, associated with the gear wheel, is adapted to normally maintain switch lever 123 closed, that is, the outer contact end thereof engages the contact member 125.

When switch 123 is closed, it will close the tilting-motor holding circuit, thus maintaining a circuit through coil 137 so that breaker 135, which controls the circuit of motor 60, will be maintained in its closed position after brush 112 is disengaged from the contact portion 107, by the rotation of drum 102. When the gear wheels 58 and 62 have completed a one-half revolution, the recess in

cam 63 will be engaged by the normally open switch 124 so that this switch can engage contact member 126.

The momentary engagement of switch lever 124 with the fixed contact member 126 closes the automatically-controlled charging-door operating circuit and will thus energize solenoid 177, this action occurring when the hearth tray being dumped is in its highest raised position. The energization of the coil of relay 177 closes the air-valve-solenoid energizing circuit, so that coil 94 is energized and core member 93 and the valve stem and the valves operatively connected therewith are in their lowered positions, unseating valve 86 and seating valve 90, so that compressed air may flow into chamber 78 from conduit 92 and into the pipe 77 to operate the door-raising device. The charging door 67 is thus raised to permit of charging the second tray ahead of the tray being dumped. The door will be held open for a predetermined period sufficient for charging purposes, by the interlock member 181 maintaining the energizing circuit of the coil of relay 177.

When the switch 124 has its roller end in engagement with the recess in cam 63, it will be closed, whereby the circuit through relay 177 is closed. The air-valve coil 94 will, therefore, be maintained in an energized condition until this circuit is interrupted momentarily by push-button switch 184. This deenergizes the coil of relay 177 and therefore, interrupts the circuit through coil 94. The spring 87, associated with the valve stem, will again move the air valve into the position shown, for instance, in Fig. 5 of the drawings. In this position, the supply of compressed air to cylinder 72 is shut off and permits the door 67 to move piston 70, forcing the air from cylinder 72 past valve 90 to the outside air, whereby door 67 will be closed.

When gear wheels 58 and 62 have made one complete revolution, and the hearth tray has been restored to its initial position, switch 123 will again engage the recess in cam 63 so that it will be opened, thus opening the tilting-motor holding circuit and deenergizing coil 137, thus causing breaker 135 to open, whereby the motor 60 is deenergized and the tilting mechanism is stopped.

Shortly after this, the contact member 113 of the timing-motor device will engage portion 108 of contact surfaces 104 because of the continued rotation of drum 102. This engagement closes the periodic hearth-motor starting circuit, and coil 136 will be energized, which will cause the closing of breaker 134, so that hearth motor 44 is energized to restart the conveyor 22. Rotation of the conveyor will effect the disengagement of switch 118 with lug 119, thus permitting switch 118

to be moved, by its cooperating spring, to the position shown in Fig. 3.

The continued rotation of drum 102 will cause the disengagement of contact member 113 from surface 108, and the periodic hearth-motor starting circuit will again be opened. Shortly after the holding-motor starting circuit has again been opened, the contact member 113 will be disengaged from surface 106 10 on account of the continued rotation of drum 102, whereby the timing-motor holding circuit will be opened, permitting relay switch 158 to open, whereby the timing-motor energizing circuit is opened, and the timing- 15 device drive motor is stopped.

Since the timing motor 101 may be a synchronous motor, it is obvious that the timing motor and the drum switch 102 may operate as a chronometric controlling device to 20 time the operation of the conveyor, the tilting mechanism and the charging-door mechanism. Since the motor 101 is connected to the drum through a variable-speed mechanism, the speed of rotation of the drum 102 25 may be varied within relatively wide limits.

The above described cycle of operations will be continued indefinitely in the same sequence, so long as the supply circuit is 30 energized and no change in connections is made.

If it is desired to make repairs to the conveyor or to the tilting mechanism, switch 114 is thrown to a position opposite to that shown in Fig. 3, which permits the closing 35 either of the hearth-motor inching circuit or the tilting-motor inching circuit by means of push-buttons 188 or 192, respectively.

If push-button 188 is held closed by the operator, coil 136 is energized, and breaker 40 134 will be closed, thus causing the energization and operation of motor 44 and conveyor 22. The push-button may be held closed for a time necessary to bring the conveyor to the desired position. In like manner, the tilting 45 mechanism may be caused to operate by closing push-button switch 192 and holding it closed for such length of time as will cause the members to move into the desired positions.

50 The normally open push-button switch 192 may be closed to cause the opening of charging door 67 by energizing the manually-controlled charging-door operating circuit, and particularly of coil 94. When this 55 push-button is released it will again open the circuit, permitting the valves to again move to the position shown in Fig. 5 of the drawings, so that the door 67 is again closed, as was described above.

60 Bridging members 138 and 139 and their cooperating contact members provide electric interlocking means for preventing simultaneous operation of the tilting motor and of the hearth motor. It will be noted 65 that bridging member 139 is open when mo-

tor 60 is operating, because of the closing of the main contacts, as hereinbefore described, while bridging member 138 will be disengaged from its contact members when the motor 44 is energized by closing breaker 134. The circuit through coil 137 or coil 136 being interrupted, will prevent energization of the corresponding motor.

A modified form of electric-connecting surfaces on the drum 102 to be operated by motor 101 is shown in Fig. 4 of the drawings. The drum is here provided with substantially the same electric-conducting surfaces 105, 106, 107 and 108, as hereinbefore described to cooperate with stationary contact members 109, 111, 112 and 113, and, in addition thereto, a contact portion 201 and a cooperating brush or contact member 202 are provided. The portion 201 is located in substantially the same peripheral position 80 as is portion 107. When this form of electric-conducting surface is used, conductor 182 is electrically connected to brush 202 instead of to lever 124, so that, when brush 202 85 engages surface 201, the following circuit 90 is established:

From conductor 141, through switch 143, conductor 144, through the bridging members of relays 145 and 147 connected by conductor 146, conductor 148, blade 117, conductor 149, part of conductor 151, conductor 164, the electric-conducting surfaces on drum 102, portion 201, brush 202, conductor 182, coil of relay 177, conductor 183, switch 184, conductors 185 and 186 and part of conductor 157, to supply-circuit conductor 142. This energizes relay 177 so that this relay will operate to energize coil 94 and cause door 67 to open. The air-valve holding circuit for the above-described circuit will be established 105 automatically, as was hereinbefore set forth.

Instead of employing an air valve 79 for operating the door, an electric motor may be utilized, the energizing circuit of which may be controlled in the same manner and by the same circuits as have been already described.

The energized condition of the hearth-moving motor circuit may be indicated by a visual signal 203 which is connected to contact member 113 of the timing device and to supply-circuit conductor 142, and it will therefore, be energized as long as the hearth-motor circuit is closed.

Merely by way of example and to indicate the times of operations of the respective devices, it may be noted that the operating time of the hearth motor in moving the hearth over a peripheral distance equal to the distance between the successive hearth trays is on the order of 20 seconds, while the time 115 during which the hearth-moving motor is deenergized may be varied from less than one minute to four or five minutes. A hearth tray is tilted during this time, and the second preceding hearth is reloaded, both of these 120 125 130

operations usually requiring less than the four or five minutes mentioned above. However, this time is necessary in order to insure that the material being heat treated shall remain in the furnace chamber a proper length of time to be properly treated.

If desired, I may omit the tilting motor, and, in that case, the material will be raked from the trays manually by an operator.

10 Various modifications may be made in the system and devices embodying my invention without departing from the spirit and scope thereof, and I desire that only such limitations shall be placed thereon as are imposed by the prior art or are set forth in the appended claim.

I claim as my invention:

15 The combination with a furnace, of a conveyer, an electric motor for driving said conveyer, a plurality of hearth-trays pivotally mounted on said conveyer, mechanism for tilting said hearth-trays to successively discharge material therefrom, a means for driving said tilting mechanism, a pair of normally open circuit interrupters for controlling the operation of the conveyer-driving motor and the tilting motor, respectively, electromagnets for operating said circuit interrupters, a 20 rotary drum switch for controlling the circuits of said electromagnets, a synchronous motor for chronometrically driving said drum switch, a relay for controlling said synchronous motor, and means controlled by said conveyer for initially energizing said relay.

30 35 In testimony whereof, I have hereunto subscribed my name this 17 day of November, 1926.

HARLAN S. GANO.
